CLAIM

The ornamental design for a thermo-hygrometer, as shown
and described.

DESCRIPTION

FIG. 1 is a front perspective view of a thermo-hygrometer
showing the new design;

FIG. 2 is a rear perspective view of the thermo-hygrometer
showing the new design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a perspective view of the thermo-hygrometer in use
with a support.

The broken lines in the drawings show portions of the
thermo-hygrometer which form no part of the claimed
design.

1 Claim, 9 Drawing Sheets
